GEORGE KNOX, OF NEW YORK, N. Y., ASSIGNOR OF ONE-HALF TO JOSEPH L. BAKER,
OF OMAHA, NEBRASKA.

BRINE-COOLER.

948,143.

Specification of Letters Patent.

Patented Feb. 1, 1910.

Application filed May 19, 1909. Serial No. 496,953.

To all whom it may concern:

Be it known that I, GEORGE KNOX, a citizen of the United States, and a resident of New York, county and State of New York, have invented certain new and useful Improvements in Brine-Coolers, of which the following is a full, clear, and exact description.

This invention relates more particularly to a cooler adapted for use in connection with refrigerating or cold storage plants.

The primary object of the invention is to provide simple and efficient means which will provide for a rapid flow of the liquid ammonia and at the same time permit quick escape of the gas as it is generated, thereby overcoming the objections incident to the ordinary form of coolers in which the gas is carried as a dead weight with the liquid for a considerable distance before the same can escape.

Another object of the invention is to provide a simple and efficient cooler which will be effective in use, and which will be economical in the surface required and therefore in the length of pipes and quantity of material used in its construction.

A further object of the invention is to provide a cooler which may be readily constructed and assembled, and which may be employed in various connections.

With these and other objects in view, the invention will be hereinafter more particularly described with reference to the accompanying drawings, which form a part of this specification, and will then be pointed out in the claims at the end of the description.

In the drawings, Figure 1 is a vertical section, partly in elevation, of one form of cooler or device embodying my invention; and Fig. 2 is a front elevation, partly broken away, of the cooler.

The casing 10 may be of any desired form and of any suitable construction, whether of steel, cast iron or otherwise, and at one part of the casing is an inlet 11 for the brine or other medium, and at or near the lower part of the casing is the outlet 12. The casing 10 is provided with a head 13, and an end or head 14, and extending from the heads 13 and 14 are baffle plates 15 and 16. The plates 15 project inward from the head 14, and one or more plates project inward from the head 13, and these plates are somewhat shorter than the casing, and alternate in ar-

rangement so that the brine or medium is caused to pass first from one end of the casing to the other and then back again in order to take a circuitous route through said casing, the said baffle plates 15 and 16 being inclined if desired to cause the brine or liquid to flow more easily through the casing from the inlet 11 to and through the outlet 12.

Within the casing 10 are a plurality of pipes or sections 17. These pipes may vary in number and have their inner ends closed and may be made to incline downward as shown, and at or near their inner ends may be supported by the bars 18, and their outer ends may extend through the packing glands 19 to form a tight joint with the head 13, or the said pipes may be arranged within the casing in any other preferred way. As shown there are three pipes arranged in a series, and the casing is shown as holding four independent series of pipes 17. Each pipe may be provided with a flange 20 at its outer end, and the flanges of each series of pipes may be connected to flanges 21 of a common header, device or connection 22. There are four headers 22, 23, 24 and 25, each connected independently to one of the series of pipes 17, and these headers are each provided with a flange 26 which is held to a flange 27 of a tee or other fitting 28. These fittings 28 are connected by a pipe section 29, which, with a pipe or part 30 forms with the sections 29, and fitting 28, a common pipe or connection, and said section 30 communicates with a liquid separator or tank 31, the upper part of which is provided with an outlet 32 leading to the suction of the usual compressor. By this means, and by having the pipes inclined as shown, the gas as the ammonia boils within the pipes 17, will quickly escape back into the headers 24 and through the pipe 30 into the separator and from there to the compressor.

A pipe 33 leads from the separator 31 to the upper header 22 in order that any liquid separated from the gas will pass from the separator into said connection. This header 22 is provided with an inlet pipe 34 for the ammonia, and in said pipe may be an expander or other valve 35. The header 22 has an overflow pipe 36 which projects somewhat above the lower surface of the header in order that a certain amount of the liquid ammonia may be held therein, and this pipe

leads to one end of the next header 23. At the other end of the header 23 is a similar overflow pipe 37, and leading from the header 24 to the section 25 is an overflow pipe 38. As will be seen, the ammonia is caused to pass from the upper header 22 into the overflow 36 to the header 23 through the overflow 37 into the header 24, and through the overflow 38 into the header 25. The liquid is thus caused to flow into the different headers and to be retained therein at a uniform height and some of the liquid will be caused to flow into each series of pipes 17, and by reason of their inclination will give a rapid flow of the same down the pipes till the liquid reaches the inner closed end thereof, and as the liquid ammonia within the pipes is caused to boil by the brine passing around the pipes, the gases will as readily and directly escape past the liquid and enter the connections leading to the separator 31.

From the foregoing, it will be seen that a simple cooler is provided which will provide a rapid flow of the liquid ammonia and as rapid an escape of the gas, so that the same will not have to be carried as a dead weight with the liquid; that the said cooler is simple in construction and may be readily made and assembled; that simple means are provided whereby the liquid ammonia may be held at a uniform height and may be caused to pass successively to a series of headers independent of each other, and that simple means is provided whereby the brine or medium may be caused to pass in a circuitous way throughout substantially the entire length of the casing.

Having thus described my invention, I claim as new and desire to secure by Letters Patent:—

1. In a brine cooler, the combination with a casing having inlet and outlet connections for the brine, of baffle plates extending lengthwise of the casing to cause the liquid to take a circuitous route therethrough, a plurality of series of pipes extending into the casing and arranged at an inclination to cause a liquid to flow downward from one end thereof, a header for each series of pipes, a liquid separator, connections between the separator and all of the headers, and means whereby the liquid ammonia may be caused to pass through one header to another and to retain a uniform height of liquid in each header.

2. In a cooler, the combination with a casing through which a liquid may pass, of a plurality of relatively short pipes extending into the casing and arranged at an inclination to cause a liquid to flow downward from one end thereof, and means for supplying liquid ammonia to the pipes and for permitting the gas generated therein to escape from each pipe.

3. In a cooler, the combination with a casing through which a liquid may pass, of a plurality of series of relatively short pipes extending into the casing and arranged at an inclination to cause the liquid to flow downward from one end thereof, and means for supplying a liquid to each series of pipes independently of each other and to permit the escape of gas directly from each series.

4. In a brine cooler, the combination with a casing through which a liquid may pass, of a plurality of series of pipes extending into the casing and arranged at an inclination to cause a liquid to flow downward from one end thereof, a header for each series of pipes, and means whereby liquid ammonia may be caused to pass through one header to another and at the same time permit escape of gas from the pipes.

5. In a brine cooler, the combination with a casing having inlet and outlet connections for the brine, of baffle plates extending lengthwise of the casing to cause the liquid to take a circuitous route therethrough, a plurality of series of pipes extending into the casing and arranged at an inclination to cause a liquid to flow downward from one end thereof, a header for each series of pipes, connections for the escape of gas, and means for supplying liquid ammonia to one of the headers to cause it to pass from one header to another and to retain a uniform height of liquid in each header.

6. In a brine cooler, the combination with a casing having inlet and outlet connections for a liquid, of a plurality of series of pipes extending into the casing and arranged at an inclination to cause a liquid to flow downward from one end thereof, a header for each series of pipes, a liquid separator, a common connection for the escape of gas, and independent connections for the supply of liquid to the headers.

7. In a cooler of the character described, the combination with a casing having means for the flow of brine therethrough, of a plurality of series of pipes having closed ends, a header for each series of pipes, a separator, an overflow connection between the separator and the upper header, a connection between the headers and separator whereby the gas may pass quickly from the pipes into the separator, and an overflow connection between the headers.

8. In a cooler of the character described, the combination with a casing having means for the flow of liquid therethrough, of a plurality of series of inclined pipes having closed ends, a header for each series of pipes, overflow connections between the headers, and means for supplying a liquid to one of the headers.

9. In a cooler of the character described, the combination with a casing having means for the flow of the brine therethrough, of

a plurality of series of inclined pipes, a header for each series of pipes, means for supplying ammonia thereto, an overflow connection between the headers to keep a uniform supply of liquid therein, and a common connection between the headers for the escape of gas.

10. In a cooler of the character described, the combination with a casing having means for the flow of the brine therethrough, of a plurality of series of inclined pipes having

closed ends, a header for each series of pipes, and independent connections for the supply of liquid and the simultaneous escape of gas as it is generated.

15 This specification signed and witnessed this 17th day of May A. D. 1909.
